UNITED STATES PATENT OFFICE.

JEFFERSON B. BRACKETT AND JOSEPH R. BAILEY, OF WOONSOCKET,
RHODE ISLAND, ASSIGNORS TO SAID BRACKETT AND ARCHIE L.
TALBOT, OF LEWISTON, MAINE.

BENCH FOR WRINGING-MACHINES.

SPECIFICATION forming part of Letters Patent No. 234,653, dated November 23, 1880.

Application filed June 9, 1880. (No model.)

To all whom it may concern:

Be it known that we, JEFFERSON B. BRACKETT and JOSEPH R. BAILEY, of Woonsocket, of the county of Providence and State of Rhode Island, have invented a new and useful Improvement in Benches for Wringing-Machines; and we do hereby declare the same to be described in the following specification and represented in the accompanying drawings, of which—

Figure 1 is a front elevation, Fig. 2 an end view, and Fig. 3 a longitudinal section, of a bench having our invention. Fig. 4 is a top view of the water-board, while Fig. 5 is a horizontal section of it and its supporters, to be hereinafter described. Fig. 6 is hereinafter explained.

The nature of our invention is defined in the claims hereinafter set forth.

In the drawings, A denotes a folding bench. At the middle part of it there are two wringer-supporters, B, such consisting of two arms, a, and a connecting cross-bar, b, arranged as shown. Each supporter straddles the top frame, c, of the bench, and is pivoted thereto so as to be capable of being turned down upon such frame and into the position as shown by dotted lines in Figs. 1 and 2, or up against its fellow, in manner as represented in said figures. Each supporter, when up, inclines toward the other, their two cross-bars being then in contact, as shown in Fig. 3. Thus one supporter serves as a brace to the other, especially when a wringer is fastened to their two cross-bars, which is accomplished by applying and securing it to them in the manner in which it is usually applied and secured to a tub at its edge—that is to say, by causing it to straddle the bars and to be held to them by its clamping devices.

Fig. 6 is an end view of a wringer so applied to the cross-bars of the two supporters. One or each of the said supporters has on the inner edges of its arms bearings f, for receiving the journals g of the water-board C, which, projecting from the ends of the board at their middles, enter such bearings and turn therein, and are kept in place by the supporters when elevated and against each other. On turning

one of the supporting arms from the other 50 the water-board may be separated from them. This water-board is to cause the water from the wringer to be discharged into a tub when on the bench.

The top frame of the bench is composed of 55 two pairs of bars, h, and intermediate bar, i, and two cross-bars, k, all being arranged as represented. Each leg-frame of the bench is composed of two legs, m, and connecting cross-bars n o, arranged as represented. Each of 60 the legs, at its upper part, is inserted between a pair of the bars h, and is pivoted to them, in order that when the legs are folded or turned up to the top frame they may enter or fold into the space between the said bars. Struts p p, 65 pivoted to the medial bar i of the top frame and notched at their outer ends, serve to hold the leg-frames out when the legs are bearing against the inner edge of the cross-bars k.

In using the wringer it is customary to do 70 so with two tubs placed on the bench, the wringer being above and between such tubs. The clothes, while the water is being expelled from them by the wringer, pass from one tub between the squeeze-rollers of the wringer to 75 and into the other tub, the water discharged being caused to flow back into the tub from whence the clothes are taken.

A bench provided with a single wringer-supporter is shown in the patent to S. Wiswell, 80 entitled "Reissue No. 4,097;" consequently such does not constitute our invention.

We are aware that a wringer by means of arms extending from and permanently fixed to it and pivoted to the bench is not new. 85

It will be seen that we do not have the wringer permanently connected with its supporter or to the bench, but have to the latter the two wringer-supporters adapted to sustain each other in their elevated positions as 90 well as to support a wringer and a water-board when applied to them, as explained.

What, therefore, we claim as our invention is—

1. The combination of the four arms a and 95 their two connecting cross-bars b with the bench A, such arms being pivoted to the bench, and the arms and bars being arranged and ap-

plied relatively to each other and the bench substantially in manner and to operate as and for the purpose set forth, each pair of the said arms and its connecting-bar constituting a wringer-supporter, as explained.

2. The four arms *a*, (of the wringer-supporters *B B*,) pivoted to the bench *A*, and provided with bearings, as represented, to grasp and receive the journals of the water-board when

arranged between such arms and the wringer-supporters are up and in contact with each other, all being substantially as set forth. 10

JEFFERSON B. BRACKETT.
